US00D755134S

(12) **United States Design Patent**
Andre et al.

(10) **Patent No.:** **US D755,134 S**
(45) **Date of Patent:** **** May 3, 2016**

(54) **THERMAL DEVICE**(71) Applicant: **Apple Inc.**, Cupertino, CA (US)(72) Inventors: **Bartley K. Andre**, Palo Alto, CA (US); **Jeremy Bataillou**, San Francisco, CA (US); **Brett Degner**, Menlo Park, CA (US); **Jesse Thomas Dybenko**, San Jose, CA (US); **William Francis Leggett**, San Jose, CA (US); **Nicholas Alan Rundle**, San Jose, CA (US); **Mikael Silvanto**, San Francisco, CA (US)(73) Assignee: **Apple Inc.**, Cupertino, CA (US)(**) Term: **14 Years**(21) Appl. No.: **29/510,950**(22) Filed: **Dec. 4, 2014****Related U.S. Application Data**

(63) Continuation of application No. 29/424,273, filed on Jun. 10, 2012, now Pat. No. Des. 721,338.

Primary Examiner — Selina Sikder(74) *Attorney, Agent, or Firm* — Saidman DesignLaw Group, LLC(57) **CLAIM**

The ornamental design for a thermal device, as shown and described.

DESCRIPTION

FIG. 1 is a front perspective view of a thermal device showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The drawings include CAD lines that represent contour and not surface decoration.

1 Claim, 5 Drawing Sheets(56)
